His Attorney,

UNITED STATES PATENT OFFICE.

JAMES J. WOOD, OF FORT WAYNE, INDIANA, ASSIGNOR TO GENERAL ELECTRIC COMPANY, A CORPORATION OF NEW YORK.

MAGNETO FLASH LAMP.

Application filed May 4, 1922. Serial No. 558,376.

To all whom it may concern:

Be it known that I, JAMES J. Wood, a citizen of the United States, residing at Fort Wayne, in the county of Allen, State of Indiana, have invented certain new and useful Improvements in Magneto Flash Lamps, of which the following is a specification.

The present invention relates to magneto flash lamps and has for its object to improve and simplify their construction.

For a consideration of what I believe to be novel and my invention, attention is directed to the accompanying description and the claims appended thereto.

In the drawing, which illustrates one of the embodiments of my invention, Fig. 1 is a view in side elevation of my improved lamp with a portion of the casing broken away; Fig. 2 is a longitudinal section of the magneto and associated parts; Fig. 3 is an exploded perspective view of the parts of the driving gears; and Fig. 4 is a similar view of the parts of the generator.

5 indicates the casing which is cylindrical in form, is made of thin sheet metal and of a size to be conveniently carried in the hand. It is provided with a cover 6 at one end, the flange 7 of which makes a good friction fit 20 with the inner wall of the casing. The cover is made removable so that the generator or magneto can be removed and replaced without disturbing the gear driving mechanism. The cover is also provided 30 with a fixed cross strip 8 which has an opening to receive the squared end of the generator spindle 9. On the spindle is mounted the stationary armature 10, the latter comprising an H-shaped laminated iron body 11 and a winding 12 which extends lengthwise of the body. One end of the winding 40 is grounded on the armature body and the other end passes through the hollow inner end 13 of the spindle and is connected to the small insulated contact device or button 14. Surrounding the armature is a rotating, 45 permanently magnetized field structure comprising two hardened steel pole pieces 15 and 16, each of which is substantially semi-circular in outline. This structure is carefully ground to size and is supported by two non-magnetic end heads 17 and 18 which are united by two non-magnetic screws 19, the latter occupying the spaces between the pole pieces. The heads are supported in such

manner as to rotate around the spindle 9 as a center, there being a slight radial clearance between the revolving magnet and the enclosing casing. At the lower or rear end the head 18 is sleeved directly on the 60 spindle while the head 17 at the upper or front end has fastened to it the hub of a ratchet wheel 20 which in turn is sleeved on the spindle. It is through this ratchet wheel that the field is rotated. The construction 65 of the pawl which co-operates with the ratchet and its mode of operation will be described later. There is no permanent connection between the generator and its associated driving gearing. This is a highly 70 desirable arrangement since it facilitates assembling and also enables the generator to be removed and replaced at will and by simply removing the cap 6, no tools of any kind being necessary for this purpose. 75

Referring now to the gear mechanism for driving the rotating part of the generator, it is important that the gearing be of such character that the rotor of the generator can be spun at high speed and for a considerable 80 period of time by each successive movement of the actuator; also that the gearing be simple and reliable in construction with minimum losses due to friction and that the mechanism be capable of being removed or 85 inserted in the casing as a unit. A consideration of the following will show that the gearing fulfills the above conditions. The gearing is mounted in a relatively narrow rectangular frame comprising two U-shaped pieces 21 and 22, the plane of division being longitudinal and in line with the axis of the magneto or generator spindle. The division is made in this manner to facilitate the assembly of the actuating gears. 90 Located within the frame and extending cross-wise are two shafts 23 and 24, both being supported at their ends in bearings carried by the frame. Shaft 23 is positively rotated by a gear fixed thereon while 95 shaft 24 merely forms a support upon which other gears turn but which may rotate due to the slight friction of one of its supported gears.

The front ends of the frame are united 105 by the screw 25 which also forms the pivot for the segmental gear 26 which is biased to its initial position by the coiled retractile or torsion spring 27. One end of the spring 110 is attached to the frame as at 28 while the

other end is connected to the gear as at 29. The gear 26 meshes with a low speed pinion 30 sleeved on the shaft 24, and in order to avoid interference with the shaft 23 said gear is provided with an elongated opening 31 through which said shaft extends. This arrangement permits of the use of a gear of relatively large pitch diameter and because of that fact the force necessary to move it is correspondingly reduced. The rim of the gear is made thicker than the supporting part so as to provide teeth of sufficient size to minimize wear. The pinion 30 is mounted on a sleeve 32 which extends from the center of the frame outwardly. On the outer end of the sleeve is secured a ratchet wheel 33 and co-operating with it is an over-running pawl 34 which is normally pressed into engagement with the teeth of the ratchet wheel by the spring 35. The pivot for the pawl is carried by a spur gear 36 so that when the segmental gear 26 is moved against the action of the biasing or retractile spring said spur gear 36 is caused to revolve but when the segmental gear is moved in the opposite direction due to the action of its retractile spring the pawl overruns the teeth on the ratchet and the gear 36 continues to revolve in the same direction. In other words, the purpose of the arrangement is to convert the oscillating movement of the segmental gear into continuous rotary movement of the spur gear 36.

The large spur gear 36 meshes with a small intermediate speed pinion 37 which is fixed on the revolving shaft 23 and in this manner an increase of speed of said shaft is obtained. On the opposite end of the shaft 23 a large intermediate speed gear 38 is fixed which in turn meshes with a small pinion 39 that is sleeved on the shaft 24 and in this manner a further multiplication of speed is obtained. On the same sleeve which carries the pinion 39 is a large beveled gear 40 which in turn meshes with a small beveled pinion 41 whereby a further increase of speed is obtained for a given movement of the segmental gear 26. The use of spur gears for the initial portion of the driving mechanism which are carried by spindles extending perpendicular to the axis of the lamp casing, and bevel gearing for the final portion enables me to arrange the gearing in a casing of small diameter which is so desirable in a device of this character and also to use a generator of small diameter.

The beveled pinion 41 is secured to a hollow sleeve 42 which in turn is located in a bearing carried by the meeting parts of the frame 21-22. The rear part of the frame is united by two screws 43 located at the sides of the bearing. On the sleeve 42 is mounted a disk 44 which carries one part of a centrifugal coupling, the other part be-

ing attached to the generator. The coupling includes a pawl 45 and ratchet wheel 20. The construction of this pawl is important. As the lamp depends for its operation on attaining a relatively high rotative speed of the field magnets of the generator, I so design the pawl that its operation is dependent upon centrifugal force. To this end one part of the pawl forms a tooth for engagement with the ratchet teeth and the other a tail piece 46 which moves outwardly due to centrifugal force and overbalances the tooth and causes the latter to move inwardly into engagement with the ratchet teeth. With such a construction when the speed of the propelling gears falls below that of the spinning generator the tooth will be disengaged from the ratchet and the parts will be free. This is important because if the pawl should drag over the teeth of the ratchet it would act as a brake to decrease the speed of the generator and hence the duration of the light for a given impulse of the actuator. The arrangement also facilitates assembling the parts, since by setting the pawl in its inoperative position, that is to say, with the tooth and tail both outside the circle defining the ends of the teeth, the generator and its ratchet can be slipped into the casing from the rear, and with the certainty of proper engagement of the parts when the generator is rotated. On account of the fact that it is necessary to have the generator spin as long as possible for each movement of the actuator, the rotating field is purposely made heavier than is necessary for electrical reasons so as to have substantial flywheel effect. For the same reason, the bearings should be carefully made to reduce friction as much as possible.

As previously stated, one end of the armature winding is connected to the insulated contact 14 which is mounted on the spindle 13, the latter extending through the hollow sleeve of the beveled pinion into the area defined by the gear frame. To convey current from the contact 14 to the lamp a spring 47, Fig. 3, is provided which has a small opening 48 to receive the contact. From this point the spring extends to the outside of the gear frame, thence along one of its flattened sides to the outer end where it is held by a screw 49 which is located in an insulating bushing. The bushing is held in place by the screw 25 which also unites the outer ends of the frame. From the screw the spring is continued to form the central terminal 50 with which the center terminal of the lamp 51 engages.

The outer or front end of the casing is provided with a tubular member 52 which makes a snug fit therewith, a bead being provided to ensure proper seating relation. Inside of the member is located a reflector 130

58 which has a screw-threaded recess to receive the base of the lamp, said reflector also forming the ground side of the circuit. The reflector and the lens 54 or other glass 5 is held in place by the nut or shell 55.

Referring now to the hand actuator: This comprises a lever 56 which has a pivot 57; the pivot is made with a screw at one end and a slotted eye at the other, said screw 10 serving as the means to unite the main casing with the detachable member 52 which carries the lamp and its associated parts. The lever is made narrow near its pivot and spreads out at the other end to form 15 a suitable gripping surface. The lever is connected to the pivot 57 by a screw, and to the segmental gear by a link 58. The link is provided with a shoulder 59 which is adapted to engage the inner surface of 20 the main casing 5 when the handle is moved to the position shown in Fig. 1 which is the locked, carrying position. That is to say the handle has not only been moved to a position close to the casing but has also 25 been moved slightly longitudinally to permit the shoulder to engage the casing, the latter action being permitted by the slotted eye in the pivot 57. When unlocked the retractile spring 27 tends at all times to 30 move the free end of the actuator lever or handle to the end of its stroke and away from the casing, hence it is desirable to lock the actuator in the retracted position 35 for greater convenience in carrying the lamp about when not in actual operation. In operation the casing is held in the hand with the fingers arranged to grasp the lever and move it toward the casing. At the inner end of the stroke the squeezing action of 40 the fingers is released and the retractile spring restores the lever preparatory to a second operation or impulse. A stroke of the lever for example every few seconds will be sufficient to keep the generator field 45 spinning and the lamp lighted.

In accordance with the provisions of the patent statutes, I have described the principle of operation of my invention, together with the apparatus which I now consider 50 to represent the best embodiment thereof, but I desire to have it understood that the apparatus shown is only illustrative and that the invention may be carried out by other means.

55 What I claim as new and desire to secure by Letters Patent of the United States, is:—

1. In a device of the character described, the combination of a casing, a generator 60 located within the casing and extending longitudinally thereof, a frame also located within the casing which extends longitudinally thereof and has transverse shafts, gearing arranged on the shafts and within 65 the frame, a centrifugal coupling for con-

nnecting the gearing with the rotor of the generator, an actuator which extends outside of the casing for driving the gearing, a lamp carried by the casing, and means for carrying current from the generator 70 to the lamp.

2. In a device of the character described, the combination of a casing, a generator located within the casing and extending longitudinally thereof, a frame also located 75 within the casing which extends longitudinally thereof and has transverse shafts, spur gearing mounted on one of the shafts, cooperating spur and bevel gearing mounted on the other shaft and capable of independent rotative movements, a beveled pinion which meshes with said bevel gear, a shaft for the pinion which is in axial alignment with the generator, a centrifugal coupling for connecting the pinion shaft with the 80 rotor of the generator, an actuator which extends outside of the casing for driving the gearing, a lamp carried by the casing, and means for carrying current from the 85 generator to the lamp.

3. In a device of the character described, the combination of a casing, a generator located within the casing and extending longitudinally thereof, a frame also located 90 within the casing which extends longitudinally thereof and has transverse shafts, cooperating gearing mounted on the shafts, an overrunning clutch for connecting and disconnecting the gearing on one shaft with that on the other, a segmental gear pivotally supported by the frame which drives a gear on one of the shafts, an actuator for the segmental gear which extends to the outside of the casing, a retractile spring for 95 said gear, a centrifugal clutch, one member of which is driven by the gearing, the other being connected to the generator, a lamp carried by the casing, and means for carrying current from the generator to the 100 lamp.

4. In a device of the character described, the combination of a cylindrical casing, a generator located within the casing and extending longitudinally thereof, said generator having a stationary armature and a 115 rotating field magnet, the latter also acting as a flywheel, a non-rotating spindle on which the armature is mounted, means for supporting said magnet on the spindle, a frame located in the casing and extending longitudinally thereof, a pair of transverse shafts mounted in the frame, a train of cooperating gears mounted on the shafts, an overrunning clutch in the train whereby oscillating movement of one gear is converted 120 into continuous rotary motion of another gear, means connecting the gearing with the field magnet which includes a centrifugal clutch, a reciprocating actuator whereby successive impulses are imparted to the gear 125 130

train, a lamp, and means for carrying current from the generator to the lamp.

5. In a device of the character described, the combination of a casing, a generator located therein, a frame also located in the casing, and extending longitudinally thereof, a shaft carried by the frame and extending crosswise thereof, a pinion on one of the shafts, an oscillating segmental gear for 10 driving it, a pivot for the gear mounted on the frame, a gear loosely mounted on the shaft, an overrunning clutch between said pinion and the gear, a beveled gear also mounted on the shaft, a pinion for driving 15 it, a second shaft parallel with the first which extends across the path of movement of the segmental gear, speed multiplying gearing carried by the shaft which meshes with gearing on the first mentioned shaft, 20 a pinion meshing with the beveled gear on the first named shaft, a centrifugal clutch, one member of which is driven by the beveled pinion, the other being attached to the rotor of the generator, an actuator for the 25 segmental gear, a restoring spring for the gear, a lamp, and means for conveying current from the generator to the lamp.
6. In a device of the character described, the combination of a casing, a frame mounted therein and extending longitudinally thereof, a pair of cross shafts carried by the frame, low and high speed gearing mounted on one of the shafts, intermediate speed gearing mounted on the other shaft, 30 a segmental oscillating gear carried by the frame for driving the low speed gearing, an overrunning clutch which permits oscillating movements of the segmental gear to be transformed into continuous rotary motion 35 of the low speed gearing, a generator, and means driven by the high speed gearing for rotating the generator which includes an overrunning clutch that permits the gener- 40

ator to rotate at a speed different from that of the high speed gearing. 45

7. In a device of the character described, the combination of a casing, a generator located therein adjacent one end and extending longitudinally thereof, which comprises a stationary coil wound armature and a magnetized rotating field magnet, a spindle upon which the armature and magnet are both mounted, the former being fixed in position while the latter rotates, a removable end cap for the casing at the generator end thereof 50 for releasably holding the generator therein, said cap providing means for preventing the spindle from turning, a contact carried by the spindle which is connected to one end of said coil, the other end being grounded, 55 gearing and overrunning clutches located in the casing for rotating the magnet, an oscillating actuator means, one of said overrunning clutches being located in the gearing adjacent the actuator means and another located in the gearing adjacent the rotating magnet, a retractile spring for the actuator means, a lamp, and a spring which conveys current from the contact to the lamp. 60

8. In a device of the character described, 70 the combination of a casing, a generator, gearing within the casing for driving the generator which includes a segmental gear, a retractile spring for the gearing, a lever which extends longitudinally of the casing 75 and on the outside thereof, a pivot for the lever which has a slotted eye, and a link which is connected to the lever at one end and to the gear at the other end, said link having a shoulder which engages the wall 80 of the casing when the lever is moved to a predetermined position to lock said lever against the action of said spring.

In witness whereof, I have hereunto set my hand this 1st day of May, 1922.

JAMES J. WOOD.
